BALLAST REMOVING MACHINE

Joseph H. Walbridge, Battle Creek, Mich.

Application September 15, 1932
Serial No. 633,371

20 Claims. (Cl. 37—104)

The main objects of this invention are:

First, to provide a machine adapted to remove old ballast and establish a new sub-grade under existing railway track, where it is desired to renew or replace the ballast.

Second, to provide a machine of this character, which not only eliminates the necessity of manually "skeletonizing" the track, as in prior practice, but will also create a true grade.

Third, to provide a ballast removing machine which may be used for all kinds of ballast and on single, double, or more track road beds.

Fourth, to provide a machine of this character, which is simple and economical in its parts and efficient and effective in operation.

Objects relating to details and economies of my invention will appear from the description to follow. The invention is defined and pointed out in the claims.

20 A structure which is a preferred embodiment of my invention is illustrated in the accompanying drawings, in which:

Fig. 1 is a fragmentary views mainly in side elevation of a machine embodying the invention 25 in operative relation to a track.

Fig. 2 is a fragmentary top plan view.

Fig. 3 is a rear end elevation.

Fig. 4 is a view similar to Fig. 3, showing the scrapers in inoperative position by full lines and 30 in operative position by dotted lines.

Fig. 5 is a top plan view of the scraper, the possible adjustments thereof being shown by dotted lines.

Referring to the drawings, 1 is a road bed having a railway track 2 thereon consisting of spaced rails 3 and cross ties 4. The machine comprises a front truck 5 and a rear truck 6, the trucks being provided with track lifting power jacks 7 and 8, respectively. Inwardly facing channel-like substantially horizontal side guide members 9 are pivoted at their forward ends 10 to the sides of the front truck 5 and pivotally and slidably connected to the sides of the rear truck 6, the latter being provided with a cross shaft 11 having rollers 45 12 at the ends thereof disposed in said channel-like guide members 9, as illustrated by Fig. 3.

Each of the guide members 9 carries an outwardly facing channel-like way member 13 suspended therebelow by spaced end hangers 14, the rear end hanger being provided with a brace 15. The way members 13 support for reciprocatory movement scraper carriages 16 which comprise slides 17 having wheels 18 disposed in the channel-like way members 13 and vertical supports or 55 hangers 19 hinged to the slides at 20, whereby

they may be swung outwardly and upwardly, as illustrated by Fig. 4. To the lower ends of the supports 19 are pivoted the scraper sections or members 21 and 22 which are pivotally connected at their inner ends, the scrapers being provided with pivot brackets 24 and 25 for this purpose, the arrangement being such that the scraper members, as illustrated by Fig. 5, may be arranged to form a V or a substantially continuous diagonal scraper, the dotted lines 26 illustrating the 65 scraper section 22 alined with the scraper section 21 for this purpose. The vertical pivots 27 between the vertical supports 19 and the scrapers facilitate the adjusting of the scrapers relative to each other.

When it is desired to move the scraper members to inoperative position, as illustrated by Fig. 4, they are disconnected at 23, swung outwardly about their pivots 27 until parallel with the way members 13 and then swung outwardly 70 and upwardly about the hinges 20, the scrapers resting on the tops of the guide members 9 when swung to their inoperative position.

The carriages 16 are adapted to be advanced by the windlasses 28 mounted on the front truck 5 and having cables 29 extending rearwardly therefrom and connected to the upper ends of the supports 19, the latter being provided with braces 30 hinged at the top the same as the vertical supports 19. The windlasses 28 are preferably adapted to be driven by the power unit of the front truck 5. The windlasses are designed to be driven together or independently, the detail of the driving means not being shown.

In operation, the front and rear trucks 5 and 6 are arranged in their spaced or extended relation. The power jacks 7 and 8 are then set in operation to raise the track 2 sufficiently to clear the top of the scraper which is positioned ahead of the rear power jack 8 under the track 2. The 90 windlasses 28 are then connected to the power unit of the front truck to advance the carriages 16 which move the scraper through the old ballast 31 under the track 2. The carriages 16 are advanced until they reach a point adjacent the 95 front truck 5. Power jack 8 is then operated to lower the track 2 onto the new sub-grade and is then advanced to a point 32 just behind the scraper carriages. The rear power jack 8 is then 100 set in operation to raise the track 2 sufficiently to bring it to the same elevation as the front jack 7. The front power jack is then operated to clear the track 2 and the front truck 5 is advanced to a point 33, the predetermined distance 105 ahead of the rear truck, and the front jack 5 110

is thereupon set in operation to raise the track 2 to the desired elevation and the windlasses 23 are again operated to advance the carriages 16 to scrape out the old ballast, as described 5 above. This procedure is repeated as the "skeletonizing" progresses.

When it is desired to move the scraper to inoperative position, for example, when the machine is advanced through turn-outs or permanent 10 highway crossings, the scraper members are disconnected as described above and swung into inverted position on top of the guide members as described above.

From the above description, it will be apparent 15 to those skilled in the art that I provide an improved ballast removing machine which is highly effective in operation, the machine being provided with means for maintaining the true grade of the road bed. While I have not gone 20 into detail concerning the means for controlling the operation of the various power units, it will be understood that conventional controls are used.

In order to facilitate the adjustment of the 25 apparatus to a predetermined grade, pointer fingers 34 are provided which project laterally from some fixed part of the frame into position to cooperate with a grade stake or the like.

I have illustrated and described my improvements in an embodiment which I consider very 30 practical. I have not attempted to illustrate or describe other embodiments or adaptations, as it is believed this disclosure will enable those skilled in the art to embody or adapt my improvements as may be desired.

Having thus described my invention, what I claim as new and wish to secure by Letters Patent is:

1. A ballast removing machine comprising a 40 front truck having a track lifting power jack, a rear truck having a track lifting power jack, horizontal side guide members pivoted to said trucks and slidably relative to the rear one, horizontal carriage way members carried by said 45 guide members, carriages supported by said way members for reciprocatory movement and having a pair of scraper members hung therefrom and detachably and pivotally connected at their inner ends, and means on said front truck for advancing said carriages.

2. A ballast removing machine comprising a 50 front truck having a track lifting power jack, a rear truck having a track lifting power jack, horizontal guide members pivoted to said trucks and slidably relative to one of them, horizontal carriage way members carried by said guide members, carriages supported by said way members for reciprocatory movement, scrapers mounted on said carriages, and means for advancing said carriages.

3. A ballast removing machine comprising a 60 front truck having a track lifting jack, a rear truck having a track lifting jack, guide members pivoted to said trucks and slidably relative to one of them, carriage way members carried by said guide members, carriages supported by said way members and a scraper hung therefrom and comprising pivotally and detachably connected sections, and means for advancing said carriages.

70 4. A ballast removing machine comprising front and rear trucks each having track lifting power jacks associated therewith, guide members mounted on said trucks and slidably connected to one of them, way members carried by said 75 guide members, and carriages mounted for re-

ciprocatory movement on said way members and having a scraper comprising two sections connected together and normally positioned under the track and said sections when disconnected being each adapted to be swung to inoperative position on the top of one of said guide members.

5. A ballast removing machine comprising front and rear trucks each having track lifting jacks associated therewith, guide members on said trucks and slidably associated with one of them, way members carried by said guide members, and carriages mounted on said way members and a scraper on said carriages.

6. A ballast removing machine comprising trucks each having track lifting jacks associated therewith, guide members carried by said trucks, way members carried by said guide members, and carriages mounted on said way members and having a scraper comprising sections mounted to be swung to inoperative position on the tops of said guide members.

7. A ballast removing machine comprising trucks each having track lifting jacks associated therewith, guide members carried by said trucks, way members carried by said guide members, and carriages mounted on said way members and having a scraper.

8. A ballast removing machine comprising a front track lifting power jack unit, a rear track lifting power jack unit, inwardly facing channel-like side guide members pivoted at their forward ends to said front unit, and slidably and pivotally connected to said rear unit, outwardly facing channel-like side way members carried by said guide members and suspended therebelow, carriages carried for reciprocatory movement on said way members and having vertical supports hinged to swing outwardly and upwardly and scraper members pivoted to said supports and hinged together under the center of the machine, and means for advancing said supports.

9. A ballast removing machine comprising a front track lifting power jack unit, a rear track lifting power jack unit, side guide members pivoted at their forward ends to said front unit, and slidably and pivotally connected to said rear unit, way members carried by said guide members and suspended therebelow, carriages carried for reciprocatory movement on said way members and having vertical supports hinged to swing outwardly and upwardly and scraper members pivoted to said supports and hinged together under the center of the machine, and means for advancing said carriages.

10. A ballast removing machine comprising a front track lifting power jack unit, a rear track lifting power jack unit, side guide members pivoted at their forward ends to said front unit, and slidably and pivotally connected to said rear unit, way members carried by said guide members and suspended therebelow, carriages carried for reciprocatory movement on said way members and having scraper members hinged together under the center of the machine, and means for advancing said carriages.

11. A ballast removing machine provided with substantially horizontal way members, and carriages mounted on said way members for reciprocatory movement and having scraper supports hinged thereto and scraper members pivoted to said supports and pivotally connected at their inner ends.

12. A ballast removing machine provided with

- way members, and carriages mounted on said way members for reciprocatory movement and having scraper supports hinged thereto and scraper members pivoted to said supports and pivotally connected at their inner ends. 5 and slidably associated with one of them to permit independent movement of the trucks on a track, and a scraper adapted to be arranged beneath an elevated track and slidably supported by said way members at the sides of the track. 80
13. A ballast removing machine provided with carriage way members, and carriages mounted on said way members and having scraper supports and a pair of scraper members pivoted to said supports and pivotally and detachably connected. 10
14. A ballast removing machine provided with carriages having scraper members hinged thereto and pivotally connected at their inner ends, and spaced guide members, the scraper members being adapted to be moved to inoperative position 15 on the tops of said guide members. 85
15. A ballast removing machine provided with carriages having scraper members hung therefrom and pivotally connected at their inner ends, 20 whereby they may be adjusted relative to each other. 90
16. In a ballast removing machine, the combination of a pair of trucks adapted to travel on a railway track and carrying track lifting means, 25 way members pivotally mounted on said trucks and slidably associated with one of them to permit independent movement of the trucks on a track, a scraper adapted to be arranged beneath an elevated track and slidably supported by said 30 way members at the sides of the track, and means for propelling said scraper mounted on one of said trucks. 95
17. In a ballast removing machine, the combination of a pair of trucks adapted to travel on a railway track and carrying track lifting means, 35 way members pivotally mounted on said trucks 100
